WORK HOLDER FOR LAPPING LATHES

Henry H. Silverman, Jamaica, N. Y.

Application December 10, 1946, Serial No. 715,272

1. Claim. (Cl. 51—228)

1

This invention relates to devices for grinding or lapping small decorative metallic objects of an ornamental character associated with watches, jewelry, and the like.

In lapping an article, the same is ground, polished or worn away by a rotary disc of soft metal, wood, leather, or other material that is charged with an abrasive or polishing powder. In this manner various objects are cut or shaped to a desired configuration or form, the same being applicable to hard and soft metals and other materials.

Heretofore the practice in lapping has been to hold the object in ones hand thus to present it to the rotary grinding or polishing element, sometimes with the aid of an improvised support or attachment. The results obtained lacked accuracy. Thus if a polygonal article was being lapped, the different sides would vary in length or otherwise.

It is therefore an object of the invention to provide improved means for avoiding the difficulties mentioned.

Another object of the invention is to furnish improved means of a particularly simple and inexpensive nature, and desirably applicable to existing lathes for performing lapping operations with uniformity and precision, and yet with the required convenience and flexibility of manipulation.

Another object of the invention is the provision of a device of the nature set forth having improved means for presenting the work at any required angle to the face of the lap while the feeding of the work may be performed manually to suit the judgment and "feel" of the skilled operator.

Another object of the invention is to furnish a device of the type mentioned having an improved precision-adjusted work table adapted to very closely approach the lap for accurately supporting extremely small objects.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claim, and illustrated in the annexed drawing, wherein like parts are designated by the same reference characters throughout the several views.

In the drawing:

Figure 1 is a fragmentary view in side eleva-

2

tion showing a device embodying the invention.

Fig. 2 is a sectional view taken approximately on the broken line 2—2 of Figure 1 but with certain conventional parts shown in elevation.

Fig. 3 is a horizontal sectional view through the bed of the lathe showing the base of my attachment as applied thereto.

Fig. 4 is a side view of an angular adjusting element carrying the work table, a portion of which is shown in section.

Fig. 5 is a top plan view of the work table and its angular adjusting element of Figure 1.

The advantages of the invention as here outlined are best realized when all of its features and instrumentalities are combined, but useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes the bed of any conventional lathe, the same comprising a pair of bars 11 and 12 suitably grooved or otherwise shaped as at 13 to form a track along which is adjustably movable any suitable tool or work holder, in this instance the base 14 of a motor 15 carrying a lap 16 of a type hereinbefore described.

The usual practice is that the lap 16 is rotated by a horizontal shaft 17, with the lap lying in a vertical plane parallel to the lathe bed 10. However, the invention is not limited to this particular arrangement, because the lap 16 may also rotate in a horizontal or other plane.

Formed in the bars 11 and 12 of the lathe bed 10 are the holes or openings 18 for slidably receiving the horizontal shafts or rods 19 and 20, this serving to exemplify a carriage or track projecting from a side of the lathe and serving for movement of the work toward and away from the lap 16. By passing the rods 19 and 20 through both of the bars 11 and 12, a strong and accurate support is obtained. Mounted on the rods 19 and 20 is a frame 21 desirably of a skeleton character, and so fixedly related to the rods 19 and 20 as to afford a carrier that is rigid in construction and precise in movement. The frame 21 may consist of the spaced bars 22 and 23, fixed to the rods as by being pinned thereto at 24. Also passing through the bars 22 and 23 is a screw 25 attached to the bed 10 to the lathe 55 and being desirably pinned thereto at 26 if

necessary. To permit free passage of the screw with relation to the bars 22 and 23, the openings 27 therein afford a clearance with the screw. In the space 28 between the bars 22 and 23 is a circular nut 29 or the like threaded upon the screw and fitted with precision between these bars, the structure being such as to avoid any lost motion or backlash. Similarly snugly fitted in the space 28 is an arm 30 pivoted on the bars 22, 23 by a pin 31 extending therethrough. Also disposed in the space 28 is a stop element 32 for a purpose hereinafter described. This element is formed with a hub 33 receiving the rod 19 and being adjustably locked thereon as by a set screw 33a.

It will now be seen that upon turning the nut 29, the frame 21 is movable toward and away from the bed of the lathe without disturbing any of the parts carried by said frame.

The arm 30 is generally upright but desirably at an angle to the vertical. Threaded in this arm is a set screw 34 bearing upon the relatively fixed stop member 32. The latter may be so shaped as to obtain any desired rate of change of angle of the arm 30 by turning the set screw 34. As the angle changes, the point at which the set screw bears on the stop shifts along the latter. A rotatable or angularly movable disc-like member 35 is pivoted at 36 on the arm 30 at the upper end thereof. This pivot may be offset with relation to the lap shaft 17. For a coarse angular adjustment of the member 35, the lower section thereof may constitute a gear 37, the upper portion of the arm 30 being forked at 38 to receive this gear section. Suitable means is provided mounted on the arm 30 for releasably selectively engaging the teeth of the section 37. Accordingly the arm 30 may have a slot 39 therethrough communicating with the adjustment gear teeth. On one side of the arm are the lugs 40 for pivotally mounting at 41 a finger 42 which passes through the slot 39 to the opposite side of the arm 30. The upper edge of the finger 42 is shaped to accurately fit between the gear teeth to adjustably lock the member 35 without backlash. A tension coil spring 43 is connected to the finger piece 42 and to a lock 44 on the arm 30 thereby maintaining the finger piece in locking position subject to easy release when the operator depresses the free end of the finger. It will be noted that the member 35 is angularly adjustable in the plane of the adjustment afforded by the set screw 34 and provides a coarse but rapid adjustment while the set screw 34 furnishes a fine adjustment. The coarse adjustment is of a precision character.

Formed in the upper portion of the member 35 is an open-ended slot 45 for snugly receiving an interchangeable member 46 adapted to project to any desired degree beyond the member 35. This member 46 is fixedly secured in position by pins 47, 48 passing through the member 35. The member 46 is formed with an open-ended slot 49 for receiving a depending flange 50 of the work table 51. The pin 47 passes through this flange 50 whereby the work table 51 is settable about an axis at right angles to the adjustments provision described. The flange 50 and the work table 51 taper toward the lead edge 52 of the work table to permit this edge to be in close proximity to the lap 16 in different angular positions of the work table. At this rear edge, the work table may be formed with a downwardly and outwardly depending wall or flange 53. Fixedly connected or integrally formed with the

member 35 is a generally rectangular frame 54 having a rear section 55 and side sections 56, the latter inclined downward if necessary according to the shape of the member 35, to which they are affixed. The frame 54 embraces the flange 53 and affords ample room for tilting of the work table about its axis 47. The tilting movement of the work table is controlled by a plurality of vertically spaced set screws 57, 58, threaded through the frame section 55, and respectively located above and below the pivot axis 47 and adapted to abut the flange 53. For angularly setting the work table 51 either one of the screws is moved toward the right and the other in the opposite directions, and then both screws are tightened to hold the work table fixedly in a required angular position.

The operation of the device will now be briefly described. The work table 51 affords a smooth plane surface whose leading edge 52 is in close proximity to the rotating lap 16 so that small articles that are to be lapped are caused to rest snugly on the work table, and are fed toward the lap directly by the fingers of the operator who relies upon his skill and judgment to produce the proper degree of grinding or polishing. I have found that this operation and method of control is ample for all practical purposes to anyone skilled in the art. It provides a precision guide while at the same time facilitating the use by the operator of "feel" to obtain the desired results in a much more convenient and suitable manner than if a mechanical feed were used which might not be adapted for very small articles and which would interfere with the "feel" to which the operator is accustomed. Because the work table approach is very close to the lap, an adequate support is furnished even for relatively minute objects. The lap may also be coated with rouge or other materials for furnishing a very high polish.

The device is set up for use by first giving the member 35 a coarse adjustment, which is done by depressing the finger 42 to release the gear teeth and then turning the member 35 to a desired angular position of the work table. Then the finger 42 is released so that the spring 43 holds the member 35 locked. Now a fine adjustment of the angle is obtained by manipulation of the set screw 34. Then the set screws 57 and 58 are actuated to give the work table an angular adjustment in the opposite direction. Finally the nut 29 is turned to advance the work table to a proper relation to the lap 16.

It will be appreciated that the arm 30 may also be utilized for a vertical setting of the work table by manipulation of the set screw 34, and this can be further increased by changing the angular setting of the stop 32 for which purpose the set screw 33a may be used. Accordingly the work table can be used with laps of different diameters and at varying distances from the centers thereof. The lap may also be moved longitudinally of the lathe bed by moving its base 14 along the same to a desired position in which it may be locked by any well-known means that need not be shown herein. The weight of the work table and its associated parts will suffice to hold the set screw 34 snugly against the stop 32, but if required, additional means may be furnished for that purpose.

The invention is readily applicable to existing lathes by perforating the same to receive the elements 19, 20, and 25 whereby my attachment can be mounted thereon without interference with any of the other parts of the lathe.

I claim:

A device including a support having a plurality of holes therein, a horizontal carrier including a plurality of rods slidably mounted in said holes, a frame having a plurality of bars fixedly mounted on the rods, said bars being spaced from each other to provide a vertical opening therebetween, a screw connected to the support and passing through the bars in parallel relation to the rods, a nut on the screw fitted in said space for actuating the frame toward and away from the support, and arm fitted in said space, a pivot pin for the lower end of the arm passing through the bars, an adjusting screw for angularly setting the arm carried by the latter, the frame having a seating portion for the end of the screw, a disc mounted on the arm at the upper end thereof for angular movement in the plane of the disc, which plane is parallel to the frame, the disc having teeth along the lower edge thereof, means carried by the arm for selectively releasably engaging the teeth to set the disc, a work table mounted on the disc at the upper part thereof for angular move- 15

ment about a pivot at right angles to the plane of the disc, the work table having a depending flange, a frame element connected to the disc and extending around the flange in spaced relation thereto, and set screws in the frame above and below the pivot of the work table and engaging the flange to cause angular setting movement of the work table.
